UNITED STATES PATENT OFFICE.

WYATT RICHARD R. FRYE, OF WASHINGTON, DISTRICT OF COLUMBIA.

PHOTOGRAPHIC-PRINTING APPARATUS.

1,275,239.

Specification of Letters Patent. Patented Aug. 13, 1918.

Application filed February 17, 1916. Serial No. 78,874.

To all whom it may concern:

Be it known that I, WYATT RICHARD R. FRYE, a citizen of the United States, and a resident of the city of Washington, in the 5 District of Columbia, have invented certain new and useful Improvements in Photographic-Printing Apparatus, of which the following is a specification.

This invention relates broadly to the art 10 of printing from photographic negatives, and has for its principal object the production of an apparatus in which the printing may be accomplished by means of artificial light.

15 Another object of the invention is to provide means for suitably controlling the light employed so that the intensity thereof may be varied relative to any particular portion of the film in order to produce an even 20 print from an unbalanced negative.

Another object of the invention resides 25 in the combination of means for controlling each of the lights as above referred to with means operated independently thereof and upon the final positioning of the negative 30 for automatically and simultaneously lighting all of the lights which have been previously manually thrown into circuit.

Other and further objects of the invention 35 will in part be obvious and will in part be pointed out in the specification herein-after following by reference to the accompanying drawings forming a part thereof and in which like characters have been used 40 to represent like parts throughout the several views thereof.

Figure 1 is a perspective view of my improved photographic printing apparatus. Fig. 2 is a perspective view of a modification. Fig. 3 is a diagrammatic view of the wiring system. Fig. 4 is a cross-sectional view of the apparatus shown in Fig. 1 with the platen in closed position. Fig. 5 is a detail view of a switch and the operating 45 means therefor. Fig. 6 is an enlarged cross-sectional view on the line B—B of Fig. 1. Fig. 7 is a detail view showing a lamp mounting.

In the devices heretofore employed for 50 printing from photographic negatives, by means of artificial light, it has been customary to vary the position of the light source relative to the negative in order to produce an even print irrespective of the 55 density of the negative used. This method is objectionable for the reason that it re-

quires considerable time to position the light and does not sufficiently control the light to produce a clear, even print. In printing from negatives having one portion 60 thereof considerably thicker than another portion it is necessary that some means be provided for increasing the brilliancy of the light adjacent the thick portion of the film and decreasing the same adjacent the thin 65 portion. Such control of each of the lamps employed enables the operator to produce an even print, and by providing a plurality of electric lamps so arranged that one is adjacent each corner of the film, with an 70 individual switch for each of the lamps in convenient reach of the operator, this regulation may be quickly and positively accomplished.

Referring more particularly to the drawings, the main body 1 of the photographic device is provided with a lining of asbestos or other suitable material 2 which is securely held in place by a protective covering of noninflammable material such as tin. 75 The upper side of the body of the device is provided with an opening 5 adapted to receive a ground glass or other suitable plate 6 upon which the negative together with the paper is placed for the printing operation. 80 In order to hold the paper and negative in close contact with the glass plate and to prevent relative movement between the two there is preferably provided a platen 7 composed of three parts hingedly connected together. The platen is secured in position on the apparatus by means of the nuts 8 which are adapted to be adjusted to provide more or less room as desired between the platen and the plate, to accommodate either a plate 85 or a film. In order to accomplish this adjustment, the platen and the coöperating portion of the body of the device may be provided with counter sunk spring sockets 9 for the reception of adjusting springs 10. 90 For operating the platen there is preferably provided a transverse bar 11 suitably secured between the bifurcated ends of an upright post 12 carried by the device adjacent one of the sides thereof. Each of the sections of the platen has a split post 14 thereon for receiving and guiding the transverse bar 11, and these posts are preferably provided with rollers 15 adapted to run on the transverse bar as a track. For firmly holding 100 the platen in position there are provided suitable compression springs 16 on each of 105 110

the posts, these springs being held in position by the follower blocks 17, and their upward movement limited when the parts are in open position by the stops 18. By 5 providing stops and follower blocks as herein shown to coöperate with the rollers 15 friction between the parts is greatly reduced and the operation thereby facilitated. After the platen has been manually operated, 10 and in order to automatically return the same to its normal or open position as shown in Fig. 1, there is provided a U-shaped member 19 carried by the transverse bar 11 and having its ends curved to pass through the 15 guide blocks 20. Each of the legs of the U-shaped member is preferably provided with an abutment 21 adapted to compress the open coil spring 22 against the guide blocks when the platen is moved to closed 20 position. By reason of this compression of the open coil spring it is apparent that upon release of the platen the spring will tend to resume its normal position and thereby move the platen to its open position. To 25 facilitate the assembling of the parts the transverse bar may be cut away along the lower edge to receive the U-shaped member, and provided with suitably constructed guard plates 24 for holding this member 30 in position.

In Fig. 2 I have shown a slightly modified form of my invention which is more particularly adapted for commercial use where it is desired to produce a great number of prints in a short time. In this form the main body of the device is carried by supporting legs 25 which are reinforced and held in position by the cross-bars 26. Pivotally mounted on one of the cross-bars 26 35 is a treadle 27 having the front end thereof projecting through an operating yoke 28 which is carried by the levers 29 pivotally mounted on opposite sides of the body of the device on pivots 30. The opposite ends 40 of the levers 29 are connected by a cross-rod 45 31. In this form of the device the platen is preferably provided with two or more transverse bars having extensions 32. For operatively connecting these extensions with the 50 cross-rod there may be provided links or other suitable connecting members 34. The parts are returned to normal position after operation by closed coil springs 35 secured in any suitable manner to the forward ends 55 of the levers 29.

For furnishing the artificial light, I preferably employ a plurality of incandescent lamps 36, 37, 38 and 39. As shown diagrammatically in Fig. 3, one of these lamps is 60 preferably positioned within the main body of the device adjacent each corner thereof and beneath the corresponding corners of the ground glass plate in the upper side of the device. These lamps are controlled by 65 means of switches 36', 37', 38', and 39', suit-

ably mounted exteriorly of the casing and within convenient reach of the operator, the switch 36' controlling the lamp 36 and so on. The feed wires 40 and 41 for the lamps are adapted for connection with any suitable source of electricity through the medium of a detachable coupling 42. One terminal of each of the lamps is connected to the feed wire 40 by the wire 43, and the other terminal is connected to the feed wire 41 by means of the connecting wires 44, the switches 36', 37', 38', and 39', and the return wire 45. By means of the switches before referred to, each of the lamps may be individually controlled, and by reason of this control the intensity of the light adjacent any desired portion of the ground glass plate may be changed in order to allow for films having heavy and light portions. For example, if the portion of the film above the lamp 36 is comparatively heavy, and the portion adjacent the lamp 39 is thin, the lamp 36 would be turned on by means of the switch 36', and the lamp 39 would be turned off by means of its controlling switch 39'. In order to simultaneously control all of the lamps manually so that it can be readily seen which ones have been thrown into circuit, and thereby permit visualization of the lighting conditions, there is provided a manually operated switch 46 in the return wire 45. This switch 46 is connected in parallel with a second switch 46' which is operated by the rod 47 mounted for vertical movement in the front of the body 1. The upper end of the rod 47 is guided within the casing 48 carrying a spring 49 which tends to hold the rod 47 in its elevated position by reason of its pressure against the cross-head 50. For operating the rod 47 to close the switch, the transverse bar 11 is preferably provided with a pin 51 adapted to pass through the opening 52 and engage the upper end of the switch rod, and depress the same into the position shown in Fig. 4. For holding the platen in its closed position, the pin carries a suitably constructed latch 54 normally projected into forward or engaging position with the plate 55 by means of a spring 56 engaging the tail 57 of the latch.

In the modification shown in Fig. 2 the switch 58, which corresponds to the switch 46', is operated through the medium of the rod 59 passing through the treadle 27 and provided with cross-heads 60 adapted to engage the opposite sides of the switch for closing and opening the same respectively.

The apparatus being adapted for use in a dark room, I have provided a non-actinic lamp 61 which is directly connected to the feed wires and is thereby in circuit at all times for enabling the operator to properly position his materials on the glass plate. If I so desire, I may provide the body of the device with a door 62 which may be opened

- at will by the operator to permit the insertion or removal of vignetting plates 64 carried in the grooves 65 suitably formed interiorly of the device.
- 5 The operation of my improved photographic printing apparatus is as follows: The switch 46 is manually operated to complete the circuit leading to the individual controlling switches 36, etc., and these individual switches are all manually operated to control the incandescent lamps in the desired manner in accordance with the negative from which the print is to be made. The lamps having been suitably controlled, 10 the switch 46 is turned to cut all of the lamps out of circuit. The negative and the paper are then properly positioned on the ground glass plate by means of the light given from the non-actinic lamp. The platen is then operated either through the medium of the transverse bar or the treadle, and by reason of the three-part construction 15 grips the rear edge of the paper first and thereby prevents creeping of the same.
- 20 After the platen has completed its downward movements the transverse bars compress the springs to produce an even pressure throughout, and by this final compression the pin is moved into engagement with the rod 47 to close the switch 46. The closing of this switch automatically throws into circuit all of the lamps which had formerly 25 been manually controlled. It is desirable that the light should not be turned on until all of the parts are firmly held in position, and it will be apparent that this is accomplished in my device by the final compression of the springs, or in the modification by the distance between the cross-heads 30 60.
- Having thus described my invention what I claim is:
1. In a photographic printing apparatus, a frame, a platen carried thereby, said platen being composed of a plurality of sections, posts carried by each of said sections, compression springs surrounding each of said posts, a transverse bar carried by said frame and passing through said posts for operating the platen, and anti-friction 35 means for said bar in each of said posts, 50 said anti-friction means permitting said posts to change their angular relation to the transverse bar during opening and closing movements of the platen.
2. In a photographic printing device of the character specified a portable light proof box, a plurality of actinic electric lamps within said box and adapted to be lighted at the will of the operator, a non-actinic lamp also within said box and adapted to be continuously lighted, a light transmitting window on the top of said box, a manually operated platen adapted to cover said window, in combination with a plurality of light switches mounted on the side of said box, there being an independent switch for each actinic lamp, an automatic switch controlling the current to said switches, said automatic switch being operated by the closing of the platen, and a hand controlled switch also mounted on the side of said box and connected in parallel with the said automatic switch whereby current to the actinic lamps may be supplied independently of the automatic switch to enable the operator to 65 70 75 visualize light conditions within the box when the platen is open.
3. A photographic printing apparatus of the character described comprising in combination a box carrying a plurality of actinic electric lamps, one side wall of said box being inset to provide a casing, a door for closing said casing, a window in the top of said box and adapted to support a suitable photographic negative, a platen constructed to cover said window, means for operating said platen, a plurality of manually controlled switches mounted on said side wall, there being a switch for each actinic lamp, an automatic switch for controlling the electrical current being supplied to the said manually operated switches, said automatic switch being operated by the platen closing means, and means for visualizing the effective light conditions of 80 85 90 95 said actinic lamps when the platen is open.

WYATT RICHARD R. FRYE.
